UNITED STATES PATENT OFFICE

112,524

DESIGN FOR A GUARD FOR AUTOMOBILE
FENDERS

Stanley J. Gurns, Chicago, Ill., assignor to The
Norlipp Company, Chicago, Ill., a corporation
of Illinois

Application September 2, 1938, Serial No. 79,706

Term of patent 7 years

To all whom it may concern:

Be it known that I, Stanley J. Gurns, a citizen of the United States and a resident of Chicago, in the county of Cook and State of Illinois, have invented a new, original, and ornamental Design for a Guard for Automobile Fenders, of which the following is a specification, reference being had to the accompanying drawing forming a part thereof.

Referring to the drawing:

Fig. 1 is a front elevation of a guard for automobile fenders showing my design;

Fig. 2 is a top plan view thereof showing the clamps in dotted lines; and

Fig. 3 is an end elevation also indicating in dotted lines the position of one of the clamps.

The dominant features of my design are shown in full lines in the drawing.

I claim:

The ornamental design for a guard for automobile fenders, as shown and described.

STANLEY J. GURNS.
